UNITED STATES PATENT OFFICE

WILLIAM HALLACK, OF DEARBORN, MICHIGAN

ELECTRICAL MEASURING INSTRUMENT

Application filed December 21, 1925. Serial No. 76,919.

This invention has for its object to simplify and render less expensive electrical measuring instruments, particularly ammeters of the type used on motor vehicles, and is concerned both with the mechanism of the device and the casing whereby it is enclosed.

As to the latter, it comprises a cup-shaped shell and a cover between which and the shell a face plate or dial, preferably of celluloid or similar material, is directly clamped.

The instrument mechanism proper involves several new and desirable features, principally (1) a means for so intensifying the field of the conductor that the need for a coil is avoided, (2) the mounting of the pointer on the conductor, thus dispensing with a number of parts ordinarily used, and (3) a manner of mounting the magnet in the casing without the use of additional parts. Other features will be noted as the description proceeds.

In the drawings, Fig. 1 is a front view of a preferred embodiment of the invention; Fig. 2 is a similar view, the shell cover and glass face being removed; and Figs. 3 and 4 are sectional views on lines 3—3 and 4—4 respectively of Fig. 2.

1 indicates a cup-shaped shell of brass, zinc or other suitable non-magnetic material, which with the associated shell cover 2 and face plate 3 carried by the latter make up the casing. I preferably arrange the forwardly turned annular flange of the member 1 within the closely fitting rearwardly turned flange of the cover and make it of such depth as to press on the face plate 3 when the parts are assembled, thus avoiding the necessity for retaining rings or other equivalent devices such as are ordinarily used. I also preferably make the face plate of celluloid (although glass may be used) and either ink or cover its inner surface with paper to provide an opaque field having a transparent slot 5, through which the pointer, hereinafter described, may be seen and read by reference to the graduated arc 6.

Within the casing, which may be varied widely from the desirable construction shown, is a conductor or bus bar 10, preferably consisting of a substantially flat strip of metal of shape resembling the letter U. Internal

washer or washers 12 and external washers 13, together with terminal bolts 14 and nuts 15, serve to rigidly mount the conductor within the shell and to insulate it therefrom. For convenience in assembly, the heads 16 of the bolts may be flattened on their upper side and held from turning by means of forwardly turned end portions 17 formed on the corresponding legs of the conductor (Fig. 3). Associated with the conductor is a permanent magnet 20 which in the construction shown is an open ring held in place within the shell by spring tension but which may be made in other suitable forms and held in place by other means. It will be observed that the intermediate portion of the conductor lies along or in the more intense portion of the magnetic field. The conductor is provided at the middle of its lower edge with a forwardly extending arm 21 having an upturned end portion 22. By positioning the magnet about the conductor and spacing it therefrom as shown, less tendency toward depolarization exists than would be the case were the magnet placed in the more intense part of the field of the conductor.

Mounted between the conductor proper and the part 22 is a pivot 30 arranged perpendicular to the face of the instrument and carrying a pointer or needle 31 and a counterweight 32 therefor, both preferably of non-magnetic material; likewise an armature 33, preferably of soft steel, positioned in such manner as to hold the pointer, when no current is flowing in the conductor, at the zero indication on the dial. The armature is also in the field which exists about the intermediate portion of the conductor when current flows therein, it being understood that the lines of force in said latter field intersect the armature at substantially right angles to those of the permanent magnet, thereby causing deflection of the needle in one direction or the other dependent on the direction of current flow, that is, whether charging or discharging, when the instrument is applied to the electric system of an ordinary vehicle or the like. It will be noted that the movement of the needle counterweight 32 is limited by the portion 21 of the conductor, thereby

preventing the pointer from contacting with the casing. Thus the insulation of the conductor is the only insulation needed.

Manifestly the construction thus far described has the merit of simplicity and low cost as compared with ammeters in ordinary use, but it would not ordinarily be sufficiently sensitive for the purpose. I therefore mount upon the conductor at a point opposite the armature a soft iron pole piece 40 which preferably lies flat against that side of the conductor farthest from the armature and which serves to concentrate the lines of force and thereby intensify the field of the conductor where it acts on the armature. The pole piece may be secured to the conductor in any suitable way such as by soldering or by prongs 41 bent over along the upper and lower edges of the conductor as shown.

It will be noted that the terminal bolts or binding posts 14 are arranged substantially along a common diameter of the shell 1; thus the intermediate portion of the conductor and the pivot on which the pointer is supported are located well toward the circumference of the shell, thereby permitting the use of a needle and associated scale of proper length, while at the same time the posts are separated from each other sufficiently to afford ease of connection of the wiring.

I claim:

1. An electrical measuring instrument comprising a conductor, means for establishing a magnetic field about said conductor at substantially right angles to the field resulting from the flow of current therethrough, a pivotally mounted armature supported solely by said conductor in the intersection of said fields and adapted to be deflected in a direction depending upon the direction of flow of said current, and a pole piece fixed to said conductor and supported thereby in position to intensify the magnetic field to which the armature is subjected.

2. An electrical measuring instrument comprising a permanent magnet, a conductor intersecting the field of said magnet and having a forwardly and upwardly extending portion, a spindle having its ends supported respectively on said portion and on the adjacent remaining part of said conductor, an armature carried by said spindle and being subject to the field of the magnet and also to the field existing about the conductor when current is flowing therein whereby the armature is deflected in one direction or the other depending on the direction of said current, and a pole piece fixed to said conductor and supported thereby in position to intensify the magnetic field to which the armature is subjected.

3. An electrical measuring instrument comprising a casing substantially circular in cross section, a substantially U-shaped conductor insulated from the casing, binding posts co-acting with the upper ends of the limbs of said conductor to support the latter, a permanent magnet in the casing with the more intense portion of its field substantially on the line of the mid portion of said conductor, and an armature mounted in said field to swing about an axis substantially parallel to that of the casing, the direction of movement of the armature being dependent on the direction of flow of current in said conductor.

4. An electrical measuring instrument comprising a cup-shaped shell of non-magnetic material, a permanent magnet of the open-ring type conforming to the inner wall of said shell and held therein by spring tension, a conductor associated with said magnet and having a portion in the field thereof, and an armature in the common field of said magnet and said conductor and deflectable in a direction dependent on the direction of flow of current in the latter.

5. An electrical instrument comprising a support, a one-piece flat substantially U-shaped conductor carried thereby and insulated therefrom, binding posts connected to the respective end portions of said conductor, a permanent magnet, means including an armature and a pointer supported by said conductor and influenced by the magnet and by the magnetic field resulting from flow of current in said conductor to indicate the direction of said flow.

6. An electrical measuring instrument comprising a substantially U-shaped conductor the limbs of which lie substantially in the same plane, a permanent magnet surrounding the conductor and spaced therefrom and having the more intense portion of its field about and substantially parallel to the mid-portion of the conductor, a pole piece fixed to the mid-portion of the conductor, and a pivoted armature in said intense portion of the field of the magnet.

7. An electrical measuring instrument comprising a substantially U-shaped conductor the limbs of which lie substantially in the same plane, a permanent magnet arranged with the more intense portion of its field about the mid-portion of the conductor and substantially parallel thereto, a pole piece fixed to the mid-portion of the conductor and positioned closely along one face thereof, and an armature on the opposite side of said conductor in the field of said magnet and also in the field of the conductor when current flows therein.

8. An electrical measuring instrument comprising a casing substantially circular in cross section, a substantially U-shaped conductor insulated from the casing, binding posts co-acting with the upper ends of the limbs of said conductor to support the latter, a permanent magnet in the casing with the

more intense portion of its field substantially on the line of the mid portion of said conductor, and an armature mounted in said field to swing about an axis substantially parallel to that of the casing, the direction 5 of movement of the armature being dependent on the direction of flow of current in said conductor.

9. An electrical measuring instrument 10 comprising a casing forming a substantially cylindrical wall, a permanent magnet of the open-ring type within said wall, said magnet being so constructed and arranged that when inserted in the casing it expands into 15 engagement with said wall whereby the magnet is held in place within said casing.

In testimony whereof I affix my signature.
WILLIAM HALLACK.
